NECKTIE

Valentine Naftali, Pelham Manor, N. Y., assignor
of thirty-three and one-third per cent to
Rudolf Naftali, Pelham Manor, and thirty-
three and one-third per cent to Henry Naftali,
New York, N. Y.

Application February 18, 1939, Serial No. 257,039

1 Claim. (Cl. 2—146)

This invention relates to neckties. More particularly my invention relates to an improved construction for neckties of the four-in-hand type.

5 One of the objects of my invention is to provide an improved necktie construction of the character described, which shall be so designed that so-called large flared end neckties may be so produced without the necessity of using more
10 material than is customarily used for making four-in-hand neckties without such large flared ends.

Another object of my invention is to provide a necktie construction of the character described
15 which shall be so designed that the longitudinal stretching forces will be symmetrically aligned to provide the desired resilience.

Still another object of my invention is to provide an improved necktie construction of the
20 character described which shall comprise relatively few and simple parts, which shall be relatively inexpensive to manufacture, which shall be easy to assemble, which shall be characterized by its neatness and which at the same time shall
25 be a general improvement in the art.

Other objects of this invention will in part be obvious and in part hereinafter pointed out.

The invention accordingly consists in the features of construction, combinations of elements,
30 and arrangement of parts which will be exemplified in the construction hereinafter described, and of which the scope of application will be indicated in the claim.

In the accompanying drawing, in which is
35 shown one of the various possible embodiments of this invention,

Fig. 1 is an elevational view of the rear of a four-in-hand necktie constructed in accordance with my invention;

40 Fig. 2 is a disassociated view of the parts that go to make up my improved necktie illustrated in Fig. 1, but of larger scale;

Fig. 3 is a view similar to Fig. 2 but illustrating such parts in assembled condition;

45 Fig. 4 is a diagrammatic view illustrating the method of laying out the necktie parts on a piece of material; and

Fig. 5 is a view similar to Fig. 1, with a portion
50 thereof broken away, and disclosing the front of the necktie.

Referring now in detail to the drawing, there is disclosed a four-in-hand necktie construction in accordance with my invention and comprising
55 a small tab 10 and a large tab 11 and an inter-

connecting neckband portion comprising a pair of symmetrical members 12 and 14.

It is well known that when four-in-hand neckties are constructed of certain fabrics which are of the heavier type, difficulty is experienced by
5 the wearer in tying the same due to the fact that the thickness of the material of the neckband portion will be frictionally gripped within the folds of the collar. It is also well known that in making adjustments, as to the size and position of the knot a pulling strain is placed on the necktie in the direction of its longitudinal axis
10 in order to overcome such frictional gripping. Such pulling strain may result in the distortion of the normal shape of the necktie. In order to
15 overcome this disadvantage, I have provided a necktie construction in which the neckband portion is a specifically designed independent member which may be of different material from that of the tabs. Therefore the material of the neckband may be chosen from the type which is easily
20 slidable within a collar. In accordance with my invention the necktie tabs are specifically designed as to peripheral contour whereby to provide a resilient balancing of the longitudinal
25 pulling forces placed on the necktie when it is made up into a knot by the wearer. Also by providing an independent neckband member, the tabs may be made of relatively expensive material and the interconnecting portion of relative
30 inexpensive material to thus reduce the cost of manufacture of the completed necktie.

As noted in Fig. 4 of the drawing, the tabs 10 and 11 are so designed that they may be patterned on a strip of material M in such manner
35 that there is a minimum of waste, thus effecting a great saving in the amount of material used. This is due in a measure to the arrangement of the pointed ends Y and X of the tabs 10 and 11. As a matter of fact, I have found that with a
40 necktie comprising the tabs cut in accordance with my invention, and using a strip of 24" wide material, in 102" of length I can produce the same number of neckties as would ordinarily require 160" of the same width material, when the
45 neckties are cut in the manner as heretofore practiced.

The parts that go to make up my necktie may be assembled as follows: The neckband members 12 and 14 are preferably constructed of trapezoidal shape and disposed with the sides D—F and B—G of the members 12 and 14 respectively in adjacent relationship. The sides D—F and B—G may slightly overlap if desired or they
50 may be contiguously disposed and be stitched to—
55

- gether by any suitable stitching means to form a unitary neckband member having triangular shaped notches at opposite ends thereof, the said notches being symmetrically arranged. The sides 5 C—D and B—A are attached to the sides Q—Y and P—Y respectively of the member 10 so that the pointed end Y will be disposed at the junction of the points D and B. Similarly the sides E—F and G—H are attached to the sides X—R and 10 X—S respectively of the tab 11, and with the pointed end X disposed at the junction of the points F and G. When this has been done, there results a necktie blank as shown in Fig. 3 of the drawing.
- 15 It is noted that the points X and Y of the tabs 11 and 10 respectively are arranged in opposed relationship to each other and in line with the longitudinal axis of the necktie fabric blank as shown in Fig. 3 and also in alignment with 20 the completed necktie, as in Fig. 5. When the tabs 10 and 11 and the neckband members 12 and 14 are cut on the bias, it is seen that a balancing of the resilient stretching forces will result 25 along the longitudinal axis of the necktie.
- 25 The necktie may then be completed in any customary manner of making neckties such as for example, by folding the assembled fabric blank as shown in Fig. 3, longitudinally in half and either with or without a lining superimposed 30 thereon sewing the adjacently disposed longitudinal edges of the necktie with a line of stitching on a machine or in any other manner to form a tubular necktie casing, after which the casing is reversed to form the completed necktie 35 as shown in Figs. 1 and 5. It is noted that in the larger tab 11 the edge R—W will provide an extra flare to the end of the tie, due to its angular shape with respect to the longitudinal edge X—R thus adding to the value thereof.
- 40 If desired, the assembled necktie blank shown in Fig. 3 may be sewn together by hand. In this

event the said fabric may be folded along the longitudinal fold lines 20—21 and then joining the adjacently disposed folded edges in any suitable manner.

While in the drawing I have illustrated the 5 neckband portion as comprising the two members 12 and 14, it is understood that my invention may be satisfactorily practiced by making the neckband member of a single piece of material.

10 It will thus be seen that there is provided a device in which the several objects of this invention are achieved, and which is well adapted to meet the conditions of practical use.

15 As various possible embodiments might be made of the above invention, and as various changes might be made in the embodiments above set forth, it is to be understood that all matter herein set forth or shown in the accompanying drawing is to be interpreted as illustrative and 20 not in a limiting sense.

Having thus described my invention, I claim as new and desire to secure by Letters Patent:

25 In a necktie of the character described, a pair of tab members bias cut to render them resilient to longitudinal stretch and spaced from each other in a longitudinal direction, a neckband member interposed between said tab members, the opposite ends of said neckband member being 30 provided with notches extending inwardly from the said ends, the inner ends of said tab members being shaped to conform to and being received within said notches, said neckband member being connected to said tab members by stitching along the edges of said inner tab ends and said neckband notches, said inner ends of said tab members being arranged in opposed relationship 35 substantially along the longitudinal axis of said necktie.

VALENTINE NAFTALI. 40
